FIG. 1

FIG. 4

FIG. 2

FIG. 3

FIGURE 1 is a front perspective view of an invertible oven-broiler, or the like, in a first position and showing my new design;

FIGURE 2 is an elevation thereof as seen from the right of FIGURE 1;

FIGURE 3 is a perspective view thereof in the inverted position of the invertible oven-broiler or the like as seen from the opposite end of FIGURE 1; and

FIGURE 4 is a plan view of the invertible oven-broiler or the like shown in the inverted position of FIGURE 3.

Dominant features of my design reside in the portions shown in full lines.

I claim:

The ornamental design for an invertible oven-broiler, or the like, substantially as shown and described.
